UNITED STATES PATENT OFFICE.

PETER A. COUPAL, OF SOUTH BOSTON, MASSACHUSETTS, ASSIGNOR TO BUFFALO SHOE CO., OF BUFFALO, NEW YORK, A CORPORATION OF WEST VIRGINIA.

MACHINE FOR MAKING AND DRIVING STAPLES.

1,025,248.

Specification of Letters Patent.

Patented May 7, 1912.

Application filed February 21, 1910. Serial No. 545,011.

To all whom it may concern:

Be it known that I, PETER A. COUPAL, a citizen of the United States, residing at South Boston, in the county of Suffolk and 5 State of Massachusetts, have invented new and useful Improvements in Machines for Making and Driving Staples, of which the following is a specification.

This invention relates to improvements in 10 machines for automatically making and driving staples and particularly to a staple making and driving machine which is capable of permanently connecting the upper, inner sole, and the welt of a shoe and 15 which is also capable of being employed in the manufacture of another class of shoes having no welt, in which case the staples are driven through the outer sole, the upper and the inner sole. 20 The object of my invention is to effect improvements in the wire feeding instrumentalities, whereby the wire shall be fed from the reel with accuracy and certainty and to provide means to adjust the wire feeding 25 devices and to hold the adjusting means in a predetermined position of adjustment so that the feeding devices may be instantly thrown out of action to permit the introduction of a new supply of wire and again 30 instantly thrown into their previously adjusted position ready for operation, thus effecting a great saving in time consumed in making adjustments.

Still other objects and advantages will 35 appear hereinafter.

I do not claim herein the horn pressure mechanism nor the edge gage and welt guide, but reserve these devices as the subject matter of separate applications to be 40 filed hereafter.

The invention consists in the combination and arrangement of parts set forth in the following specification and particularly pointed out in the appended claims.

45 Referring to the drawings: Figure 1 is an elevation of a staple making and driving machine embodying my invention, the same being viewed from the right hand side thereof. Fig. 2 is an enlarged front elevation of the superstructure or head of the machine. Fig. 3 is an elevation of the superstructure or head of the machine viewed from the right hand side of Fig. 2. Fig. 4 is an elevation of the superstructure or head 50 of the machine as viewed from the left of

Fig. 2. Fig. 5 is a diagrammatic view or chart illustrating graphically the paths of the various cams and showing the relation and extent of movement of each to the others, the uppermost line representing the cam nearest the back of the machine and the lowermost line representing the cam nearest the front of the machine with the others in their proper relation therebetween. 60 Fig. 6 is a detail elevation viewed from the left hand side of the machine, showing in detail the mechanism for adding spring pressure to the work supporting horn and showing also the mechanism for operating the awls, showing also the movable head. 65 Fig. 7 is an enlarged detail side elevation of a part of the horn treadle rod, showing the ratchet sleeve thereon and showing the pawl for actuating the same. Fig. 8 is an elevation similar to Fig. 6 with the exception 70 that the parts are in the position which they occupy when the horn has been depressed to admit a thick piece of stock. Fig. 9 is a detail left hand elevation showing the former or anvil with the mechanism for imparting 75 a forward and backward movement to the same, showing also the driver and throat slides and their actuating mechanisms. Fig. 10 is a detail plan section taken on line 80 10—10 of Fig. 9. Fig. 11 is a detail left hand elevation of the shoe feeding mechanism. Fig. 12 is a detail front elevation of the shoe feeding mechanism, the shoe rest being shown in section. Fig. 13 is an enlarged detail section of the shoe rest viewed 85 from the front of the machine showing a piece of stock located between the shoe rest and the work supporting horn, showing the feed point in full lines in its initial position and in dotted lines in three other positions. Fig. 14 is a detail left hand elevation of the wire feeding mechanism. Fig. 15 is a detail rear elevation of a portion of the wire feed mechanism. Fig. 16 is a detail 90 front elevation of the wire feed mechanism. Fig. 17 is an enlarged detail section taken on line 17—17 of Fig. 2. Fig. 18 is a detail front elevation of the wire feed mechanism similar to Fig. 16, but with the parts in a different position. Fig. 19 is an enlarged detail sectional elevation taken on line 19—19 of Fig. 2, looking toward the right. Fig. 20 is a detail side elevation partly in section, of the wire locking device. Fig. 21 is a plan section taken on line 21—21 of Fig. 110

20. Fig. 22 is a detail perspective view of the wire guide. Fig. 23 is a detail perspective view as viewed from the front right hand side of the machine showing the wire cutting device, the anvil or former, and its clamp, the point bending device, and the wire stripper, together with the lever which carries the upper movable wire cutter. Fig. 24 is a bottom plan of the shoe rest, the edge 5 gage, and the adjusting devices for the same. Figs. 25 and 26 show in left hand and front elevation, respectively, the welt guide which may be used as an attachment. Fig. 27 is a detail section taken on line 10 27-27 of Fig. 26. Fig. 28 is an enlarged detail sectional elevation, partly broken away, showing the anvil, shoe rest, horn, throat and driver and showing a shoe in section, partly broken away between said 15 20 shoe rest and said horn with the driver at its lowermost point, the staple being driven. Fig. 29 is a detail front sectional elevation illustrating the anvil, throat and driver with the blank supported on the anvil and the 25 lower extremities of the throat resting upon the blank preparatory to bending the same. Fig. 30 is a vertical sectional elevation viewed from the left of the machine illustrating the anvil, throat and driver with 30 35 the throat part way down, having bent the extremities of the blank downwardly to form the staple. Fig. 31 is a sectional elevation taken on line 31-31 of Fig. 30. Fig. 32 is a sectional elevation taken on line 32-32 of Fig. 28, looking toward the right.

Like numerals refer to like parts throughout the several views of the drawings.

In the drawings, referring now particularly to Fig. 1, 40 is the frame of the machine comprising a base 41, a column 42 and a head casting 43 supported thereon. Journaled in the head casting 43 is a driving shaft 44 having thereon a driving pulley 45 which may contain any desired clutch mechanism of the well known class in which the clutch is engaged by depressing a treadle connected thereto and after the treadle has been released the clutch is automatically disengaged at a predetermined point in the rotation of the shaft, and such clutches being old and well known to those skilled in the art, it will not be necessary for me to illustrate the same.

55 *Clutch operating mechanism.*—To engage and disengage the clutch, I provide a clutch treadle 46 pivoted at 47 on the base 41 of the machine. A clutch rod or link 48 is pivotally connected at its lower end at 49 to the clutch treadle 46 and at its upper end is 60 pivotally connected at 50 to a bell crank lever 51 pivoted at 52 on the frame of the machine, said bell crank lever being connected by any suitable means to a clutch, whereby the same may be thrown into and out of action.

Horn and horn pressure mechanism.—53 is a shoe rest or work plate against the under side of which the bottom of the outer sole of a shoe may be placed and 54 is a work supporting horn which is adapted to 70 enter the shoe and rest against the inner or upper side of the sole, said horn being fast to a vertical shaft 55 which is journaled in an upper bearing 56 and a lower bearing 57 on a horn treadle 58 in a well known manner, whereby said horn may be controlled in its movements vertically by said treadle. In Fig. 1 the horn is shown in its uppermost position, which position the same occupies when a piece of stock such as the sole of a shoe of minimum thickness is located between said horn and the shoe rest. The horn treadle 58 is pivotally mounted on the pivot 47 which also serves as a pivot for the clutch treadle 46. A horn treadle rod 59 is pivotally connected at 60 to the rear end of the horn treadle 58, the upper portion of said rod being arranged to slide in two guides 61 and 62 on the head casting 43 of the frame of the machine, said guides being 80 clearly shown in Figs. 6 and 8. A helical extension spring 63 surrounding the treadle rod 59 is fast at its upper end to a collar 64 fast to said rod, while the lower end of said spring is fast to a collar 65 within which 90 said rod is adapted to slide, the collar 65 being held against vertical movement by a bracket 66 which extends into a groove 67 formed in the collar 65. Thus it will be seen that the spring 63 tends to move the rod 59 downwardly. An adjustable stop screw 68 having screw-threaded engagement with the treadle rod 58 is adapted to abut at its lower end against an abutment 69, thereby limiting the upward movement of the horn 54 100 under the influence of the spring 63.

Referring now particularly to Figs. 1, 6, 7, and 8, 70 is a helical compression spring encircling the rod 59, the lower end of said spring bearing against a collar 71 fast to 110 said rod, while the upper end of said spring bears against a collar 72 which is slidably vertically upon said rod, the extent of upward movement of the collar 72 being limited by a collar 73 fast to said rod. Fast to or formed on the collar 72 is a ratchet 74 which is adapted to be engaged by a pawl 75 pivoted at 76 on a pawl carrier 77, said pawl, in the initial position of the machine, being separated from said ratchet by a guard plate or shield 78 fast to the frame of the machine. A pin 79 slidably arranged in a hole provided in the pawl carrier 77 is held in contact with the pawl 75 by a helical compression spring 80. The pawl carrier 77 is fast to a vertically slidable rod 81 which is arranged to slide in guides 82 and 83 provided on the frame of the machine. An arm 84 rigidly secured to the rod 81 carries a cam roll 85 which is located in a cam 120 125 130

groove 86 formed in a cam 87, said cam acting through the rod 81 to impart one complete reciprocation to the pawl 75 during each rotation of the driving shaft 44 to which said cam is fast.

A vertical guide pin 88 fast to a part of the frame of the machine extends downwardly through a hole provided in the arm 84 thus acting to hold said arm and the rod 81 against rotation in the guides 82 and 83. When the pawl 75 is carried downwardly, under the influence of the cam 87, said pawl passes out of engagement with the guard plate 78 and passes into engagement with the nearest tooth of the ratchet 74, thereby carrying the collar 72 downwardly and thus compressing the spring 70, thereby during such downward movement of said collar adding to the spring pressure which tends to move the work supporting horn 54 upwardly. During the upward movement of the pawl 75 the tension on the spring 70 is correspondingly diminished. It will be understood, however, that the collar 73 is so placed that the spring 70 is at all times under some tension.

In Fig. 6, the upper face of the horn 54 is at the minimum distance from the shoe rest 53, that is, the parts are so located for a shoe sole of minimum thickness. It will be seen that when the horn 54 is in this position, the collar 72 is carried downwardly by the pawl 75 very nearly the entire stroke imparted thereto by the cam 87. If, however, a thicker piece of stock is placed between the shoe rest 53 and the horn 54 so as to move the horn downwardly into the position shown in Fig. 8, the rod 59 acts to carry the collar 72 and ratchet 74 into the position shown in Fig. 8. Therefore, on the next downward stroke of the pawl 75 the same will engage the ratchet 74 at a lower point than before and consequently the action of the cam 87 will not carry the collar 72 as far as before. The purpose of this is to cause the spring pressure applied to the horn to be the same no matter what the thickness of stock may be between said horn and the shoe rest 53, for it will be understood that were it not for the provision of the mechanism just described the upward pressure on the horn would be greater with thick stock than it is with thin stock.

In the operation of the machine as will be hereinafter more fully set forth, the tension of the spring 70 is momentarily increased during the action of the awls and the driving of the staple so that the combined tension of the spring 70 and the spring 63 is at that time opposed to the action of the awls and the force of the blow of the driver.

Shoe feeding mechanism.—Referring now particularly to Figs. 11, 12 and 13, it will be seen that the shoe rest 53 is provided with a

transverse hole 89 extending therethrough, which hole a feed point or spur 90 is adapted to enter at the proper time in the operation of the machine. The feed point or spur 90 is fast to a floating lever 91 which is pivotally connected at 92 to a rocker arm 93, said rocker arm being fast to a rock shaft 94 journaled in bearings 95 and 96 on the head casting 43 of the frame of the machine. The rock shaft 94 has fast thereto a rocker arm 97 carrying a cam roll 98 located in a cam groove 99 formed in a cam 100, said cam being adapted to act through the rocker arm 97 and rock shaft 94 to impart a rocking movement to the rocker arm 93, thereby acting to impart a vertical reciprocatory movement to the floating lever 91. The lever 91 is pivotally connected at 101 to a link 102, said link being in turn pivotally connected at 103 to a rocker arm 104. The rocker arm 104 is fast to a rock shaft 105 journaled in a bearing 106 on the head casting 43 of the frame of the machine, said rock shaft having also fast thereto a second rocker arm 107. The rocker arm 107 is pivotally connected at 108 to a link 109, said link being pivotally connected at 110 to a cam lever 111 which lever is pivoted at 112 on the head casting 43 of the frame of the machine. On the lever 111 is journaled a cam roll 113 which is located in a cam groove 114 formed in a cam 115 fast to the driving shaft 44, said cam being adapted to act through the lever 111, link 109, rocker arm 107, rock shaft 105, rocker arm 104, and link 102 to impart a horizontal reciprocatory movement to the lower end of the floating lever 91. The pivot 110 is adjustably arranged in a segmental slot 116 formed in the lever 111, whereby the extent of movement of the feed point or spur 90 toward the right and left may be determined. The initial position of the feed point or spur 90 is shown in full lines in Fig. 13. The first movement of the feed spur imparted thereto by the cam 115 acts through the connections just described to move the same into the dotted position marked "2," Fig. 13. The next movement is downwardly toward the left to the position shown in dotted lines marked "3," Fig. 13, at which time the spur enters the shoe sole, this movement taking place under the combined influence of the cams 100 and 115. The spur having now entered the shoe sole, said spur is carried in a straight path toward the left into the position shown in dotted lines and marked "4" in Fig. 13, thereby feeding the shoe toward the left, Fig. 13. The spur then moves upwardly toward the left under the combined influence of the cams 100 and 115 to the position shown in full lines in Fig. 13. The feeding mechanism thus constitutes what is known as a four-motion feed, the point of the spur tracing a trapezoid, as shown in broken lines in Fig. 13.

The floating lever 91 is guided at 116' between the two guides 117, 117 and at 118 is guided between two guides 119, 119 all of said guides constituting a part of a sliding head 120. The sliding head 120 has connected thereto or formed as a part thereof a rearwardly extending spindle 121 which is cylindrical in form and is slidably arranged in a suitable bearing provided in the head 10 casting 43 of the frame of the machine, said spindle carrying at its rear end a cam roll 122 located in a cam groove 123 formed in a cam 124, said cam being adapted to impart a horizontal reciprocatory motion 15 to the head 120, whereby said head, at the proper time in the operation of the machine, is carried forward and backward. In the initial position of the machine, the head 120 stands at its extreme forward position, as shown in full lines in Figs. 6 and 8, while its rearward position is indicated by dotted lines in said figures. Thus it will be seen that at a certain time in the operation of the machine the feed spur 90 is located 20 in vertical alinement with the slot 89 so as to be adapted to enter the same under the influence of the shoe feeding mechanism and at the proper time in the operation of the machine, as will be hereinafter more 25 fully described, the sliding head 120 carries said spur forward out of vertical alinement with said slot. The sliding head 120 is held against rotation by means of a depending arm 125 fast thereto or formed thereon, said arm extending between two guide plates 30 126 which permit said head to reciprocate longitudinally but prevent the same from rotating.

Wire feeding mechanism.—Referring now 40 particularly to Figs. 14 to 22, inclusive, and also to Figs. 2 and 4, 127 is a wire reel of any suitable or desired construction, the same being journaled on a pin 128 fast to a bracket 129 which is fast to the head casting 43 of the frame of the machine. The wire 130 leading from said reel passes first through a rocker arm 131 and thence through a wire guide 132 having a flaring entrance bounded by two converging walls 133, 133 leading to a straight passage 134 formed in said guide. The converging walls 133 make it easy to start the wire into the guide when a new coil of wire is placed on the machine and introduced into the guide. 45 The rocker arm 131 has slidably arranged therein a gripper rod 135 which is adapted to contact with one side of the wire 130 at the proper time in the operation of the machine to grip said wire by pressing the same 50 against a screw-threaded adjustable plug 136 constituting an abutment located in the end of said rocker arm.

The rocker arm 131 is fast to or formed integral with a sleeve 137 which passes 55 through and is journaled in a second sleeve 138, said sleeve 138 being journaled in a bearing 139 on the head casting 43 of the frame of the machine. Fast to the sleeve 137 is a collar 140 to which one end of a helical torsional spring 141 is fast, said 60 spring being fast at its other end to a sleeve 142, while a stop pin 143 inserted in one of a plurality of holes 144 in said sleeve abuts against a portion of the head casting and holds said sleeve against rotation in one 65 direction, thereby maintaining said spring under tension. The sleeve 142 is journaled in a bearing 145 on the head casting 43 of the machine. The spring 141 is so arranged that it tends to hold the arm 131 against a 70 movable stop 146 which consists of a rocker arm fast to the sleeve 138. Fast to or formed integral with the sleeve 138 is a rocker arm 147 to which a link 148 is pivotally connected at 149, said link being pivotally connected at 150 to a rocker arm 151 fast to a rock shaft 152, said shaft being journaled in suitable bearings in the head casting 43 of the machine. The rock shaft 152 has fast thereto a second rocker arm 153 75 to which a link 154 is pivoted at 155, the lower end of said link being pivoted at 156 on the horn treadle 58. Thus it will be seen that the horn 54, which occupies varying positions owing to varying thicknesses 80 of stock placed between said horn and the shoe rest 53, acts through the horn treadle 58, link 154, rocker arm 153, rock shaft 152, rocker arm 151, link 148, rocker arm 147, and sleeve 138 to vary the position of the 85 arm 146 which constitutes a stop for the arm 131. When the horn 54 is depressed, the same acts through the connections just described to swing the stop 146 toward the left, Figs. 2, 16 and 18. The upper end of 90 the gripper rod 135 is provided with a beveled face 157, said face being adapted to engage a corresponding beveled face 158 formed on a rod 159 which is slidably arranged within the sleeve 137, the left hand end of the rod 159 passing into a hole 160 formed in a cam lever 161.

The left hand extremity of the rod 159 95 normally bears against an abutment 162 consisting of a screw having screw-threaded engagement with the lever 161, said screw having fast thereto an arm 163 by means of which said screw may be rotated to move the same out of engagement with the end 100 of the rod 159. The arm 163 is normally held in the position shown in Fig. 14 by means of a pin 164 mounted on a spring 165 fast to the lever 161. The lever 161 has journaled thereon a cam roll 166 located in a cam groove 167 formed in a cam 168 fast to the driving shaft 44, said cam being adapted to impart a rocking movement to 105 said lever at the proper time in the operation of the machine, whereby said arm acts through the rod 159 and by reason of the 110

115 120 125 130 135 140 145 150 155 160 165 170 175 180 185 190 195 200

beveled faces 157 and 158 to force the gripper rod 135 downwardly against the wire 130, thereby tightly gripping said wire against the abutment 136. The wire having thus been gripped, a rocking movement is imparted to the arm 131 to move the same from the position shown in Fig. 16 to the position shown in Fig. 18 through the instrumentality of an arm 169 having journaled thereon a cam roll 170 adapted to be engaged by a cam 171 fast to the driving shaft 44. It will be seen that the stop 146, by determining the starting point of the arm 131, determines the length of wire fed. The wire in being drawn from the reel by the arm 131 has a tendency to become pinched between the convolutions of wire on said reel and thus tends to interfere with the proper feeding of the wire from the reel. To obviate this difficulty, the reel 127 is rotated by means of a shoe 172 having frictional engagement with the periphery of one side of said reel, said shoe being fast to a pin 173 slidably mounted on an arm 174, said arm being pivoted to rock on a stud 175 fast to the head casting 43 of the frame of the machine. The shoe 172 is held in contact with the periphery of the reel 127 by means of a helical compression spring 176 bearing at one end against a shoulder 177 formed on the pin 173 and bearing at its other end against an adjustable abutment screw 178 having screw-threaded engagement with the arm 174. The pin 173 is provided with a head 179 which may be grasped by the fingers to withdraw the shoe 172 out of engagement with the periphery of the reel 127 at any time when it becomes necessary to remove said reel from the machine. The arm 174 is pivotally connected at 180 to an eccentric rod 181, said eccentric rod having fast thereto or formed integral therewith an eccentric strap 182, which surrounds an eccentric 183 formed on or fast to the driving shaft 44, said eccentric being adapted to act through said strap, said rod and said arm to impart a reciprocatory motion to the shoe 172.

When the arm 131 in its feeding movement is carried toward the right from the position shown in Fig. 16 to the position shown in Fig. 18, the shoe 172 is also carried toward the right and the reel 127 is rotated thereby in the proper direction to cause a supply of slack wire to exist between said reel and said arm and thereby taking the load off of said arm. When the arm 131 moves backward in an idle movement from the right toward the left, the cam 168, at the beginning of such movement, acts to move the lever 161 in the proper direction to relieve the pressure of the beveled face 158 against the beveled face 157, consequently, relieving the pressure of the rod 135 against the wire 130, so that

said rod does not pinch said wire at all, and said lever acts to simultaneously actuate the wire locking device which prevents the wire 130 from being drawn toward the left by the backward movement of the shoe 172 upon the reel 127 combined with the friction of the rod 135 and abutment 136 which tend to carry said wire backward. This wire locking device comprises a gripper rod 184 which is slidably arranged in a hole provided in a cutter block 185 fast to the head casting 43 of the frame of the machine, to which block the wire guide 132 is also fast. The gripper rod 184 is provided with a depression 186 having a beveled face 187 which is adapted to be engaged by a corresponding beveled face 188 formed on a rod 189 slidably arranged in the cutter block 185, the left hand end of the rod 189 being located in a hole 190 formed in the lever 161. Surrounding the rod 189 is a helical compression spring 191 which bears at one end against a collar 192 fast to said rod and at its other end against the lever 161, said spring acting at all times to maintain the wire locking gripper rod 184 in contact with the wire 130. The left hand extremity of the rod 189 is normally separated by a slight space from an abutment consisting of a screw 193 having screw-threaded engagement with the lever 161, said screw having fast thereto an arm 194. The arm 194 is normally held in the position shown in Fig. 14 by a pin 195 fast to a spring 196, said spring being fast to the lever 161, said arm being located between said pin and a lug 197 on said lever. When the lower end of the lever 161 is moved toward the right, the right hand end of the screw 193 abuts against the left hand end of the rod 189 and acts through said rod to apply a positive pressure of the wire locking gripper rod 184 against the wire 130. The arm 194 is secured to the screw 193 by means of a nut 198 having screw-threaded engagement with a portion of said screw, said nut being adapted to clamp said arm against a shoulder 199 formed on said screw. When it is desired to vary the distance between the right hand end of the screw 193 and the left hand end of the rod 189, the nut 198 is loosened and said screw is then rotated by placing a wrench upon a square head 200 formed on said screw. In like manner, the arm 163 is secured to the screw 162 by means of a nut 201 having screw-threaded engagement with a portion of said screw, said nut being adapted to clamp said arm against a shoulder 202 formed thereon, while said screw is provided with a square head 203 by means of which the same may be rotated, whereby the wire feeding gripper rod 135 may be caused to grip the wire 130 with more or less pressure.

The arm 163 is normally located between 130

the pin 164 and a lug 204 on the lever 161, said pin and said lug thereby acting to hold the screw 162 against rotation. Whenever it becomes necessary to place a new coil of wire on the reel 127, the spring supported pins 164 and 195 are pressed toward the right, Fig. 14, and the arms 163 and 194 are then rotated upwardly into contact with lugs 205 and 206, respectively, on the lever 161. This leaves the wire free from the pressure of the gripper rod 135 and the only pressure upon the wire locking gripper rod 184 is due to the tension of the spring 191. The old wire may then be removed from the wire guide 132 and wire feeding arm 131 and the free end of the new coil of wire may then be introduced.

Wire cutting and point bending mechanism.—Referring now particularly to Fig. 23, the wire in being fed through the wire guide 132 along the line A—A passes across the top of a stationary cutter 207 fast to the cutter block 185, said cutter being provided with a beveled face 208 terminating at its upper edge in a line which extends diagonally across the wire, said cutter being secured to said cutter block by means of screws 209. A movable cutter 210 is provided with a slot 211 through which a clamp screw 212 extends, said screw having screw-threaded engagement with a cutter lever 213, whereby said cutter is adjustably secured to said lever. An adjusting screw 214 having screw-threaded engagement with the lever 213 bears against the upper portion of the cutter 210, whereby said cutter may be adjusted vertically, there being a check nut 215 which locks said screw against rotation. The cutter lever 213 is pivoted to rock on a boss 216 formed on the cutter block 185, said lever having a jaw 217 in which is located a rectangular sliding block 218, said block being pivotally mounted at 219 on a bell crank lever 220.

The bell crank lever 220 which is pivoted at 221 on the head casting 43 of the machine is provided at its upper end with a jaw 222 in which a rectangular block 223 is slidably arranged, said block being pivotally mounted on a cam roll stud 224. On the cam roll stud 224 is journaled a cam roll 225 which is located in a cam groove 226 formed in a cam 227 fast to the driving shaft 44. The stud 224 is fast to a bell crank lever 228 pivoted at 229 on the head casting 43 of the machine. At the proper time in the operation of the machine, the cam 227 acts through the connections just described to impart a rocking movement to the cutter lever 213 to reciprocate the cutter 210 and cause the same to coöperate with the stationary cutter 207 to sever a piece of the wire 130 to form a blank which is subsequently bent to form a staple, as hereinafter set forth.

To prevent the blank just referred to from being carried up by the movable cutter 210 in its ascent, there is provided a stripper 230 which is secured to the cutter block 185 by means of a screw 231, the lower extremity 70 of said stripper being arranged at a sufficient distance above the upper face of the stationary cutter 207 to allow the wire to pass therebetween. Now it is desirable that the points of each staple, when the same is 75 formed, shall both lie in a plane coinciding with one side of the staple and to that end, after each blank has been cut off, the sharp end of the wire which projects through the wire guide 132 and across the upper face of 80 the stationary cutter 207 is bent transversely of the wire by means of a bending device 232 having a beveled front face 233 which engages the back edge of the tapered point of the wire and bends the same forward so 85 that the point lies in the same plane as the front face of the wire, it being understood that the wire employed is preferably rectangular in cross section.

The point bending device 232 is fast to 90 or formed integral with an arm 234 pivoted on a stud 235 secured to a shoe rest holder 236 to which the shoe rest 53 is also fast. The arm 234 extends between a block 237 and a downwardly projecting part of an L-shaped arm 238 both of which are fast to the sliding head 120, said block and said arm being shown in full lines in Fig. 3 and said arm being indicated in dotted lines in Fig. 23, there being a space between said 95 block and said arm greater in width than the width of said arm. As the sliding head 120 moves forward the downwardly extending part of the arm 238 engages the arm 234 at 239, see Fig. 23, and carries said arm 100 and the bending device 232 forward, thereby causing the front beveled face 233 of said bending device to engage and bend the projecting point of the wire forward until its previously cut face lies in the plane of the 105 front face of the wire. Subsequently, when the sliding head 120 moves backward there is a lost motion between the block 237 and the arm 234 and finally said block brings up 110 against said arm, carrying the same backward at the proper time, thereby carrying the beveled face 233 back to the rear face of the wire.

The backward movement of the wire bending device 232 is limited in extent by a lug 115 240 formed on the arm 234, said lug being adapted to engage an adjustable stop screw 241 having screw-threaded engagement with a boss 242 on the head casting 43 of the frame. In practice, the front corner of the 120 beveled face 233 should lie in the plane of the back face of the wire so as to assist in 125 properly guiding the wire and to this end such adjustment may be effected by means of the stop screw 241. Fast to the shoe rest 130

holder 236 is a wire guide 243 having a front beveled face 244 which the wire does not normally engage, but which said wire will engage should the same happen to be bent rearwardly, said beveled face being adapted to guide the moving point of the wire as it is fed beneath a beveled face 245 formed on a wire guide 246 which is supported on the wire guide 243. The advancing point of the wire, as it passes beneath the guide 246 passes along a front vertical face 247 of the guide 243.

Awl mechanism.—Referring now particularly to Figs. 6 and 8, on the slideable head 120 is mounted a vertically reciprocating awl slide 248 guided in suitable ways, said slide having fast thereto two awls 249, 249 secured thereto by means of a clamp 250 held in place by means of a clamp screw 251. The slide 248 is reciprocated at the proper time in the operation of the machine by means of a link 252 pivotally connected at its lower end to said slide and at its upper end to a floating lever 253, which lever is pivoted at 254 to the bell crank lever 228, to which a rocking motion is imparted by means of the cam 227, whereby the lever 253 is rocked on a pivot 255. The pivot 255 is connected by means of a link 256 to a pivot 257 on the treadle rod 59. It being understood that the treadle rod 59 is carried up and down by the movements of the horn 54, it will be apparent that the height of the pivot 255 varies according to the height of said horn, the arrangement being such that the points of the awls 249 in descending toward said horn always move to a predetermined distance therefrom.

In the initial position of the machine, the awls and the slide on which they are mounted occupy the position shown in full lines in Figs. 6 and 8 and at the proper time in the operation of the machine the slideable head 120 is carried toward the left, Figs. 6 and 8, to the position shown in dotted lines therein and the awls 249 descend through the hole 89 in the shoe rest 53, as indicated in dotted lines in said figures, thus making a pair of holes in the material supported on the horn 54. The awls then rise and are returned to the position shown in full lines in Figs. 6 and 8.

Staple bending and driving mechanism.—Referring now particularly to Figs. 9, 10, 23, and 28 to 32, inclusive, 258 is an anvil or former which is secured to a floating lever 259 having fast thereto a downwardly projecting stud 260 on which a rectangular block 261 is pivotally mounted, said block being slidably arranged in a groove 263 extending across the upper side of a rotatable disk 263. The disk 263 which is rotatably arranged in a suitable recess in the shoe rest support 236 has formed thereon or fast thereto a segmental bevel gear 264 which

meshes into a segmental bevel gear 265 fast to the shaft 152. In the initial position of the machine the axis of the stud 260 is substantially coincident with the axis of the disk 263 and the gear 264, as seen in Fig. 10. 70 The lever 259 is pivotally connected at 266 to a rocker arm 267 fast to a rock shaft 268 by means of a stud 269 passing through a slot 270 formed in said arm and through the rock shaft 268, being secured thereto by 75 means of a nut 271.

The rock shaft 268 is pivoted to rock in the lower end of a cam lever 272 pivoted at 273 on the head casting 43, the upper end of said lever having journaled thereon a cam roll 274 located in a cam groove 275 formed in a cam 276 fast to the driving shaft 44. With each rotation of the driving shaft 44 the cam 276 acts through the lever 272, the rock shaft 268 and rocker arm 267 to impart 80 to the lever 259 and anvil 258 one complete reciprocation during which said lever and anvil move toward the left from the position shown in Fig. 10 and consequently, the axis of the stud 260 is moved to a position at 85 some distance from the axis of the disk 263. The disk 263 being controlled by the horn 54 through the gears 264 and 265, shaft 152 and other connections hereinbefore described, it will be understood that the angular position 90 of the slot 262 is determined by the height of the horn 54, that is, by the thickness of material located between said horn and the shoe rest 53, that the angular position of the groove 262 with each rotation of the driving 95 shaft determines the location of the anvil or former 258 right and left, as viewed from the front of the machine. A wire clamp 277 pivoted at 278 on the anvil 258 is provided at its front end with a notch 279 adapted to 100 receive the wire, the front end of said clamp being pressed downwardly toward said anvil by means of a helical compression spring 105 280, see Fig. 9.

The anvil 258 is provided near its upper 110 side with a beveled face 281 and the clamp 277 is provided near its lower side with a beveled face 282 which beveled faces converge toward each other toward the right hand side of the machine. When the wire 115 is fed through the wire guide 132 and across the top of the stationary cutter 207, said wire passes between the upper side of the anvil 258 and the lower side of the clamp 277, the beveled faces 281 and 282 insuring 120 the proper passage of the advancing end of the wire between said anvil and said clamp. When the wire has been fed the proper distance, the anvil 258 and clamp 277 move rearwardly until the wire passes into the 125 notch 279, the point at which the anvil and clamp engage the wire being determined by the thickness of stock between the shoe rest 53 and horn 54 so that when the wire is severed the severed portion which consti- 130

tutes the blank from which the staple is to be formed is held by said anvil and clamp at a point midway between the two extremities of said blank. The blank having thus been formed, the same is now carried forwardly to a point beneath a throat 283, as illustrated in Fig. 29, said throat being carried by a throat slide 284 arranged to reciprocate in suitable ways in the slidable head 120.

10 A vertical reciprocatory movement is imparted to the throat slide 284 by means of a link 285 pivotally connected at its lower end to said slide and at its upper end to a 15 bell crank lever 286 having journaled thereon a cam roll 287 located in a cam groove 288 formed in a cam 289. The throat 283 is provided with a T-shaped groove 290 in which a driver 291 is arranged to reciprocate, said driver being fast to a driver slide 292 to which a vertical reciprocatory motion is imparted by means of a link 293 pivoted at its lower end to said slide and at its upper end to a bell crank lever 294 having journaled thereon a cam roll 295 located in a cam groove 296 formed in a cam 297 fast to the driving shaft 44. The blank being held by the clamp 277, the throat 283 descends from the position shown in Fig. 29 to the position shown in Figs. 30 and 31, during which time the two sides of said throat act to bend the free ends of the blank downwardly to form a staple, as shown in Fig. 31, the legs of said staple being held in opposite sides of the groove 290. The anvil 258 and the clamp 277 then retreat, or in other words, move toward the left from the position shown in Fig. 30 to the position shown in Fig. 28, thus leaving the staple held by frictional engagement with opposite sides of the groove 290.

40 At the proper time in the operation of the machine, the throat 283 descends into the position illustrated in Figs. 28 and 32 carrying the points of the staple into contact with or closely adjacent to the material into which the same is to be driven, after which the driver 291 descends and drives the staple through the material, as shown in 45 said figures, the points of the staple being clenched against the horn 54.

50 *Shoe rest, edge guide and welt guide.*—Referring now particularly to Figs. 24 and 28, the shoe rest 53 is provided in its under side with a recess 298 of irregular form, as seen in Fig. 24, said recess being provided to accommodate the lip of the channel of the outer sole of the shoe, as shown in Fig. 28 when the machine is employed in the manufacture of shoes having no welt, in which case the staple is driven through the outer sole, through the upper and through the inner sole, said recess being provided to prevent the lip of the channel from being 55 damaged by the upward pressure of the

horn 54. Thus it will be seen that the outer or tread surface of the shoe sole is pressed against the shoe rest 53 at two points on opposite sides, respectively, of the lip of the channel. Were it not for the provision 70 of the recess just described, the lip of the channel would be greatly injured by being pressed upon at intervals so that when said lip is turned down over the staples the same would present an uneven, lumpy appearance which is entirely eliminated by the employment of said recess. 75

The edge of the work is guided by an edge guide 299 slidably arranged in a groove 300 provided in the bottom of the 80 shoe rest 53, said guide being held in place therein by means of a screw 301 extending through a slot 302 formed in said guide, said screw having screw-threaded engagement with said shoe rest. From time to 85 time it becomes necessary to adjust the edge guide 299 forward or backward and to this end a link 303 is pivotally connected at one end to said guide and at its other end to an adjusting lever 304 pivotally mounted 90 on a stud 305, said stud having a rectangular head 306 located in a slot 307 formed in the shoe rest support 236. A thumb nut 308 having screw-threaded engagement with the stud 305 serves to clamp said stud to hold 95 the same at the proper point in the slot 307. The adjusting lever 304 is provided on one side with a lug 309 and carries on its other side a stop screw 310 having screw-threaded engagement therewith, said lug and said 100 screw being adapted to limit the rocking movement of said lever in opposite directions, respectively, the extent of rocking movement being determined by said screw which is adjustable. 105

By grasping the adjusting lever 304 and rocking the same the edge guide 299 may be moved backward or forward, as may be desired. It will be understood that by loosening the nut 308 the fulcrum of the lever 304 110 may be moved backward or forward as may be desired, thus determining roughly the limits of movement of the edge guide 299.

In the manufacture of the shoes, it is usually found desirable to have the staples 115 nearer to the sole edge at the heel portion than at the toe and shank portions, and it will be understood that the operator may determine the placing of the staples during the operation of the machine by rocking the 120 lever 304.

Referring now particularly to Figs. 25, 26 and 27, which illustrate the arrangement of the machine as adapted for welt shoes, 53' is a modified form of shoe rest which has not 125 a hole nor a recess corresponding to the hole 89 and recess 298 of the shoe rest 53. In performing this class of work, a welt guide 311 is secured to the shoe rest support 236, as shown in Figs. 25 and 26, by means of a 130

screw 312 located in a corresponding screw-threaded hole 313 formed in said support. The welt guide 311 is provided with a passage 314, as seen in Fig. 27, said passage 5 being adapted to receive and guide the welt in the proper relation with the inner sole and upper of the shoe, as seen in Fig. 25. The welt guide 311 is provided with a slot 315 which is adapted to receive the feed 10 spur 90.

Referring now to Fig. 1, a welt reel 316 rotatably supported on the frame of the machine is adapted to hold a coil of welt, not shown, the welt passing therefrom upwardly through a guide 317 and thence into the welt guide 311. When the machine is used in the manufacture of welt shoes, a modified form of edge guide 299' shown in Figs. 25 and 26, is employed. In changing 15 the machine over to handle one class of work or the other, the operator has merely to change the edge guide, shoe rest and welt guide, it being understood that the welt guide is entirely removed when shoes having 20 no welt are being operated upon.

Having thus specifically described the machine, I will now proceed to describe its general operation, having reference particularly to Fig. 5. The operator first 25 presses the horn treadle 58 with his foot and after properly placing the shoe upon the horn 54 with the bottom of the sole resting against the under side of the shoe rest 53, preferably placing one side of the shank 30 portion of the shoe between the horn and shoe rest. When the operator releases the horn treadle 58 the horn 54 is carried by the tension of the spring 63 assisted very slightly by the tension of the spring 70 upwardly, thereby pressing the shoe against the shoe rest. He then depresses the clutch 35 treadle 46 to start the machine and holds said treadle depressed during the entire operation upon the shoe.

40 It will be seen by reference to Fig. 5 that as soon as the machine is started the maximum horn pressure is applied, that is, the spring 70 is depressed as hereinbefore described, and the shoe is held with considerable pressure against the shoe rest. The head 120 moves rearwardly, the awls 249 descend into the work, then rise and are carried forward to their initial position. The wire is fed across the anvil, is engaged 45 and clamped thereagainst by the clamp, the cutter descends, cuts off a piece of the wire to form a blank, the throat then descends, forms the staple and carries the staple downwardly through the shoe rest and the driver then drives the finished staple through the work, after which the tension of the spring 70 is practically entirely released and the shoe feeding mechanism feeds the shoe one step toward the left, as viewed 50 from the front of the machine, the relation

of the operations of the various parts of the machine being clearly shown in a diagrammatic manner in Fig. 5, which represents the operation of the machine during one rotation of the driving shaft 44. When the staples have been driven entirely around the 70 perimeter of the shoe, the operator releases the clutch treadle and the clutch is thrown out of operation at a predetermined point in the rotation of the driving shaft so that 75 the machine comes to a state of rest in its initial position.

Having thus described my invention, what I claim and desire by Letters Patent to secure is:

1. The combination, in a machine for making and driving fasteners, of a wire reel adapted to hold a coil of wire, instrumentalities adapted to sever a piece of said wire, form the same into a fastener and 80 drive said fastener, means to feed said wire from said reel toward said instrumentalities, and means to rotate said reel in the proper direction to cause said wire to unwind therefrom.

2. The combination; in a machine for making and driving fasteners, of a wire reel adapted to hold a coil of wire, instrumentalities adapted to sever a piece of wire, 85 form the same into a fastener and drive said fastener, means to feed said wire from said reel toward said instrumentalities, and means to rotate said reel by frictional engagement in the proper direction to cause 90 said wire to unwind therefrom.

3. The combination, in a machine for making and driving fasteners, of a wire reel adapted to hold a coil of wire, instrumentalities adapted to sever a piece of wire, form the same into a fastener and drive said 95 fastener, means to feed said wire from said reel toward said instrumentalities, a device adapted to engage said reel, a rocker arm on which said device is mounted, and means to impart a rocking movement to said arm, whereby said reel is rotated in the proper 100 direction to cause said wire to unwind therefrom.

4. The combination, in a machine for forming fasteners from wire, of a wire feeding device adapted to grip a wire, means to impart a to and fro movement to said device, a wire locking device adapted to grip said wire, means to actuate said devices alternately, whereby said feeding device is caused to grip said wire to feed the same during the movement of said feeding device in one direction and whereby said locking device is caused to grip said wire and hold the same stationary during the movement of 115 said feeding device in the opposite direction, means to adjust said wire feeding device to cause the same to engage said wire with more or less pressure, means to hold said adjusting means in a predetermined position 120

125

130

of adjustment and instrumentalities adapted to sever a piece of said wire and form the severed piece into a fastener.

5. The combination, in a machine for forming fasteners from wire, of a wire feeding device adapted to grip a wire, means to impart a to and fro movement to said device, a wire locking device adapted to grip said wire, means to actuate said devices alternately, whereby said feeding device is caused to grip said wire to feed the same during the movement of said feeding device in one direction and whereby said locking device is caused to grip said wire and hold the same stationary during the movement of said feeding device in the opposite direction, means adapted to be moved to render said feeding device inoperative, means to normally hold the last-mentioned means in a predetermined position and instrumentalities adapted to sever a piece of said wire and form the severed piece into a fastener.

10 6. The combination, in a machine for forming fasteners from wire, of a wire feeding device adapted to grip a wire, means to impart a to-and-fro movement to said device, a wire locking device adapted to grip said wire, means to actuate said devices alternately, whereby said feeding device is caused to grip said wire to feed the same

during the movement of said feeding device in one direction and whereby said locking device is caused to grip said wire and hold the same stationary during the movement of said feeding device in the opposite direction, means adapted to be moved to render said feeding device inoperative, means to normally hold the last-mentioned means in a predetermined position and instrumentalities adapted to sever a piece of said wire and form the severed piece into a fastener.

15 7. The combination, in a machine for forming fasteners from wire, of a wire feeding gripper, means to impart a to and fro movement to said gripper, a wire locking gripper, a lever to which said grippers are connected on opposite sides of its fulcrum, screws having screw-threaded engagement with said lever to adjust said grippers, respectively, means to normally hold each of said screws in a predetermined position of adjustment, and instrumentalities to sever a piece of said wire and form the severed piece into a fastener.

20 In testimony whereof I have hereunto set my hand in presence of two subscribing witnesses.
